STABILIZING DEVICE FOR PICKER STICKS

Bon Huggins, Greenville, S. C.

Application September 4, 1934, Serial No. 742,669

6 Claims. (Cl. 139—150)

My invention is a stabilizing device for the picker stick of a loom.

An important object of the invention is to provide a device of the above mentioned character which will cooperate with the picker stick shoe and oscillating stand to prevent relative wobbling movements between the same.

A further object of the invention is to provide a device of the above mentioned character which will also serve as a bumper or check for the picker stick.

A further object of the invention is to provide a wear element or bushing for arrangement between the engaging faces of the picker stick shoe and oscillating stand.

Further objects and advantages of the invention will be apparent during the course of the following description.

In the accompanying drawing forming a part of this application and in which like numerals are employed to designate like parts throughout the same,

Figure 1 is an edge elevation of the stabilizing device embodying my invention, showing the same in use,

Figure 2 is a side elevation of the same,

Figure 3 is a perspective view of the device,

Figure 4 is an edge elevation of a wear element or bushing embodied in the invention, and,

Figure 5 is a perspective view of the same.

Attention being called first to Figures 1 to 3, inclusive, the numeral 10 designates the loom frame, carrying the usual lay rock shaft 11, to which is secured the oscillating stand or foot 12. Arranged beneath the stand 12 and attached thereto in the usual manner is a spring actuated drum 13, having a strap 14 connected therewith to be wound thereon by the action of the spring, as is customary. Arranged above the oscillating stand 12 is a picker stick 15, having a shoe 16 mounted upon its lower end and rigidly secured thereto by means of a bolt 17. The shoe 16 rocks longitudinally upon the oscillating stand 12, and oscillates therewith, as is customary.

The picker stick is actuated by any suitable means, indicated at 18. The foregoing description is that of the conventional elements of a loom.

My stabilizing device embodies a body portion 19 (Figures 1 to 3, inclusive) from which depends an open frame or yoke 20, preferably integral therewith. This yoke comprises spaced sides 21 and a bottom or cross bar 22, preferably integral with the sides. This bottom or cross bar is provided with an upstanding hook 23 hav-

ing connection with the outer end of the strap 14. The body portion 19 is provided near its upper end with apertured ears 24, for receiving bolts 25, which pass through apertured ears 26 of a companion clamp 27, the picker stick 15 being arranged between the elements 19 and 27, and the bolts 25 being disposed upon opposite sides of the picker stick. The body portion 19 is provided near its lower end with an opening for the passage of the bolt 17. It is thus seen that the body portion is clamped to the picker stick.

The outer end portions of the shoe 16 and the oscillating stand 12 extend through the yoke 20 with a slight clearance between the same and the sides 21 thereof. A follower or head 28 is arranged beneath the oscillating stand 12 and engages the lower face of the same near its outer end, and this follower or head is arranged between the sides 21 with a slight clearance between the same, which prevents any considerable turning movement of the follower. The follower has a sleeve 29 rigidly secured thereto and depending therefrom, and this sleeve is slidably mounted upon a vertical shaft 30, which is rigidly attached to the bottom or cross-bar 22. A suitably stiff compressible coil spring 31 surrounds the shaft 30, and is confined between the bottom or cross bar 22 and the follower or head 28 to urge the head upwardly.

The numeral 32 designates an inwardly tapering wear blade, element, or bushing, adapted to be arranged between the outer ends of the shoe 16 and the oscillating stand 12, to compensate for the wear upon these contacting end portions. 35 The element 22 is carried by a curved shank 33, rigidly secured to a plate 34. This plate has an elongated opening or slot 35 formed therein, for the passage of the bolt 17. The wear element 32 is adjusted longitudinally of the shoe 16 40 by the use of washers 36, disposed upon the bolt 17 inwardly of the same. The bolt 17 carries a nut 37.

While it is preferred to use the wear element 32 with the stabilizing device, they may be used 45 separately.

In Figures 4 and 5, the wear element is shown in use, without the stabilizing device. When the stabilizing device is omitted, the strap 14 is attached to the lower end of the picker stick, as is 50 customary. The wear element or bushing shown in Figures 4 and 5, embodies an inwardly tapering plate or blade 38 arranged between the outer ends of the shoe 16 and oscillating stand 12. This plate or blade is carried by a curved shank 55

39, having a socket or head 40, rigidly secured thereto. This socket or head is U-shaped in horizontal cross-section and is adapted to straddle the edge of the picker stick. The head 40 is clamped to the picker stick by the bolt 47 passing through an elongated slot 41 so that the head may be vertically adjusted upon the picker stick. The blade 38 is adjusted longitudinally of the shoe 16 by arranging a washer or washers 42 within the head, as shown.

10 The operation of the first form of the invention, as shown in Figures 1 to 3, inclusive, is as follows:

When the device is applied to the picker stick, the follower or head 28 engages beneath the oscillating stand 12, and the spring 31 is under tension. This spring remains under tension during the entire rocking movement of the shoe 16 upon the stand. The spring 31 and associated elements therefore serve to retain the shoe 16 in firm engagement with the stand, preventing relative lateral movements between the parts 16 and 12. In addition to this action of the device as a stabilizing connection between the picker stick and the oscillating stand, the device also serves as a check or bumper for the picker stick. When the picker stick is swung inwardly, the outer end of the shoe 16 is raised and the yoke 20 is raised with relation to the oscillating stand 12, thus causing the follower or head 28 to compress the spring 31. When the picker stick 15 is swung to the extreme outer position, the yoke 20 is also raised with respect to the oscillating stand 12 and the spring 31 compressed. The spring is permanently under suitable tension, as it is compressed when the follower or head 28 is arranged beneath the oscillating stand, as stated, but the extent of compression is increased at the ends of the movement of the picker stick. Further, when the end portions of the shoe 16 and oscillating stand 12 wear, in order that the picker stick will properly swing, the tapered wear element or bushing 32 is projected a suitable distance between the engaging faces of the shoe 16 and oscillating stand 12, the extent that the wear element 32 is to be passed between the elements 16 and 12 depending upon the extent that these elements have become worn.

50 In Figure 4, the stabilizing device is omitted and the wear element or bushing 38 is shown applied to the picker stick and arranged to pass between the engaging faces of the shoe 16 and oscillating stand 12.

55 It is to be understood that the forms of my invention herewith shown and described are to be taken as preferred examples of the same and that various changes in the shape, size and arrangement of parts may be resorted to without departing from the spirit of my invention or the scope of the subjoined claims.

Having described my invention, what I claim is:

60 1. In a device for connection with a picker stick, as a sub-combination a yoke to be attached to the picker stick and adapted to receive

the ends of a shoe and oscillating stand therein, yielding means carried by the yoke to engage the lower face of the stand, and a wear element attached to the yoke and including a blade projecting longitudinally between the ends of the 5 contacting faces of the shoe and stand.

2. In a loom, the combination with an oscillating stand, of a picker stick, a shoe secured to the picker stick to rock upon the oscillating stand and a device having a shank mounted 10 upon the picker stick and a wear blade projecting between the shoe and stand.

3. In a loom, the combination with an oscillating stand, of a picker stick, a shoe secured to the picker stick to rock upon the oscillating 15 stand, and a device connected with the picker stick, said device including a shank and a blade secured to the shank, said blade extending longitudinally of the contacting faces of the shoe and stand and arranged between the ends of 20 the contacting faces, said blade tapering toward its free end.

4. In a loom, the combination with an oscillating stand, of a picker stick, a shoe secured to the picker stick to rock upon the oscillating 25 stand, a device separate from the shoe, stand, and picker stick and including a yoke having sides and a bottom, means to clamp the device to the picker stick, the yoke receiving the shoe and stand and the sides of the yoke serving 30 as guides for these elements, a spring device carried by the bottom of the yoke and engaging the lower surface of the stand, and a device mounted upon the first named device and having a shank and a blade portion carried by the 35 shank, such blade portion being arranged between the sides of the yoke and projecting between the contacting faces of the shoe and oscillating stand to serve as a wear element.

5. In a loom, the combination with an oscillating stand, of a picker stick, a shoe secured to the picker stick to rock upon the oscillating stand, a block, a yoke rigidly secured to the block and depending therefrom and including sides and a bottom, said bottom having an attaching member, means to clamp the block to the picker stick, a spring actuated drum secured to the stand, a strap attached to the drum and secured to the attaching member, the yoke receiving therein the shoe and stand and the 50 sides of the yoke serving as guides for these elements, and a spring device mounted upon the bottom of the yoke and engaging the lower surface of the stand.

6. In a loom having a picker stick, a shoe secured to the picker stick and a oscillating stand upon which the shoe rocks; a device bodily mounted upon the picker stick and including a shank and a blade portion carried by the 55 shank, such blade portion being adapted to be arranged between the contacting faces of the shoe and oscillating stand to serve as a wear element, and means to secure the shank to the picker stick.

60 BON HUGGINS.
